(57) CLAIM

The ornamental design for a beach umbrella anchor, as shown and described.

DESCRIPTION

FIG. 1 is a side perspective view thereof;

FIG. 2 is a top view thereof; and,

FIG. 3 is a bottom view thereof.

The beach umbrella anchor is shown with symbolic break lines; the appearance of any portion of the article beyond the break lines forms no part of the claimed design.

1 Claim, 1 Drawing Sheet

FIG. 3
